[57] **CLAIM**

The ornamental design for a adjustable wrist-mountable flashlight, as shown and described.

DESCRIPTION

FIG. 1 is a top plan view of an adjustable wrist-mountable flashlight showing my new design therefor. The broken line drawing depicting a hand and forearm is for purposes of illustration only and forms no part of my design;

FIG. 2 is a rear elevational of the flashlight with the wrist band in an open position;

FIG. 3 is a top plan view;

FIG. 4 is a right side elevational view;

FIG. 5 is a front elevational view;

FIG. 6 is a bottom plan view;

FIG. 7 is a left side elevational view; and,

FIG. 8 is a front perspective view of the flashlight with the wrist band in an closed position.

FIG. 8
